SURVEYOR'S TAPE GRIPPING TOOL

Ray J. Peters and Patrick J. Campbell, both of
2227 Contra Costa Blvd., Pleasant Hill, Calif.

Filed Mar. 16, 1964, Ser. No. 79,004

Term of patent 14 years

(Cl. D54—13)

FIGURE 1 is a top plan view of a surveyor's tape gripping tool showing our new design;

FIGURE 2 is an elevational view of one side thereof;

FIGURE 3 is a bottom plan view of the tool;

FIGURE 4 is an elevational view of the tool taken of the opposite side shown in FIGURE 2;

FIGURE 5 is a front end elevational view;

FIGURE 6 is a rear end elevational view thereof; and

FIGURE 7 is a perspective view of the tool showing it in an extended position.

We claim:

The ornamental design for a surveyor's tape gripping tool, substantially as shown.
